Atty's.

UNITED STATES PATENT OFFICE.

CHARLES R. BIRDSEY, OF HINSDALE, ILLINOIS, ASSIGNOR TO THE UNITED STATES GYPSUM CO., OF CHICAGO, ILLINOIS, A CORPORATION OF ILLINOIS.

PLASTER-BOARD BUNDLE.

Application filed June 27, 1927. Serial No. 201,578.

This invention relates to plaster lath and more particularly to bundled lath.

One of the objects of this invention is to provide a simple, practical and inexpensive form of plasterboard lath.

Another object of this invention is to provide convenient and efficient means for handling and shipping the articles of manufacture.

10 A further object of this invention is to provide improved means for handling a number of pieces of lath together as a unit.

15 A further object of this invention is to provide securing means for holding and protecting a number of the elements comprising the bundle at the edges thereof.

Further objects and advantages will appear and be brought out more fully in the following specifications and drawings in which

20 Fig. 1 is a perspective view of an embodiment of this invention;

Fig. 2 is a perspective view of the same, partially broken away.

In the building industry there have been 25 developed primarily two types of gypsum board. First, wallboard which is used to replace wood lath and the usual layer of wall plaster applied thereto and which is used also to replace wood sheathing on building inte-

30 riors. Second, plasterboard which is used in the place of wood lath and to which a coat of wall plaster is applied in the same manner that it is applied to wood lath. In either type of gypsum board the same consists of a 35 gypsum core either with laminated paper plies therein, or a solid layer of gypsum, with a fibrous exterior covering on each face side thereof.

In order to permit facile handling of plaster wallboard it has been found convenient 40 to manufacture these boards in comparatively narrow widths; for instance, 16 inches has been found to be very convenient. In ordinary handling a board of this width is 45 usually limited in length to 5 to 10 feet on account of practical consideration. Such a board is light enough so that a number of them can be bound or bundled together to 50 make a package or unit which is advantageous for shipping and handling during construction.

While wallboard is at present marketed in larger sizes substantially the same advantages are to be found in the handling and shipping of this type of gypsum board.

It is the purpose of this invention to develop a bundle and a method of securing such plasterboards or wallboards together for producing the desirable results referred to.

Referring more particularly to the drawings, I show a bundle of plasterboard or wallboard made up of separate elements (1) shown between outside elements (2) placed one above the other with their edge portions (3) in substantial alignment. A binding strip of thin tough fibrous material such as tough paper or cloth (4) is applied to the edges (3) and its edges (5) are folded over and secured by gluing or pasting to the edge portions of the outside board elements (2). 70 Pressure is applied to the edges (5) and the binding strip is thereby firmly secured to the layer of boards and the ends cut or broken to coincide with the board lengths.

In the preferred form of the invention as 75 shown in Fig. 1 only the two opposite sides of the bundles of gypsum boards are provided with binding strips 4, while the other two edges of the bundle are open or exposed. Thus the binding strips 4 prevent the gypsum boards from getting out of alignment in one direction while the friction between the boards due to the tension of the binding strips 4, prevents the gypsum boards from shifting out of alignment in the other direction.

Both plasterboard and wallboard are piled in stacks in the warehouse for storage. When so piled, if they are retained in package form by any means that gives a greater thickness to the bundle at the edges than at the 90 center, this variation in thickness multiplies as the height of the stack increases, so that the top packages when in place bow down considerably in the center and in time set in a deformed curved shape. By the use of thin 95 binding strips I provide a package that has practically the same thickness throughout its width and length so that when piled in stacks all the packages lie flat and true.

When packages are bound together with 100 bands, rope or strips which project in the slightest from the surface of the package, these binding means catch on one another when one package is slid over the other as is done in piling such packages in the warehouse. By using thin binding strips such as 105 I propose, a smooth flat package is produced with no protruding binding elements that will interfere with each other in sliding one package over the other.

By using the top and bottom sheets of gypsum board with the binding strips adhesively secured to the edges thereof as the packaging medium a package or bundle is produced

- 5 which lends itself to the use of a minimum amount of extraneous material for enclosing the gypsum board and also lends itself to rapid assembly and binding of the boards in bundles or packages. The economy of the 10 operation as well as the saving in the cost of extraneous material for packaging has resulted in a package of gypsum board which may be produced at a cost far below the cost of packaging gypsum board by any other 15 means now in use. Moreover, with a package utilizing such a minimum amount of extraneous wrapping material, a distinct advantage is gained at the place of use of the gypsum board in that there is little accumulation 20 of wrapping material that must be disposed of at expense to the user. For instance, with a package in which the gypsum boards are completely enclosed by paper or other material which must be removed at 25 the place of use of the board a great quantity of this wrapping paper accumulates and in addition to the expense to the user of removing the same, creates a fire hazard until removed, which is highly objectionable. 30 The result is that a bundle or package of gypsum board is produced and one which is very compact and substantially rigid. The bundle thus formed is convenient to handle and permits the moving of a number of 35 pieces together as a unit and further provides a protection for the edges which would be subject to injury when handled separately. The bundle is therefore a more efficient form of plaster board lath and makes possible the 40 construction and erection of more lath at a given time than would be possible otherwise.

It will be readily understood that when the package constituting the present invention is being handled in transit or otherwise, the 45 flexible nature of the fibrous binding strips permits a substantial amount of weaving or flexing of the elements of the package. Under such conditions, which are quite noticeable in packages of relatively heavy 50 material, such as plasterboard, these strips are not broken or permanently distorted, but act as hinges to accommodate such weaving or flexing, while at the same time serving to protect the edges or boundaries of the elements 55 of the package that are enclosed by the strips. When the package is to be opened preparatory to using the elements thereof, the fibrous binding strips may be readily cut or ripped longitudinally and the portions thereof 60 that are thus severed may be either stripped off of the outside elements of the package or allowed to remain thereon, as desired.

While I have shown the preferred embodiments of my invention, it will be understood

that changes and modifications may be made without departing from the spirit of the invention.

What I claim is:

1. A package of flat structural elements of similar size and shape, comprising a plurality of such elements arranged in stacked relation, and means for securing said elements together in such relation, said means comprising thin relatively tough binding strips of thin paper or fibrous material having similar flexibility enclosing certain of the edges of the elements and having intermediate portions unattached thereto and under tension due to the application of substantial compacting force to said elements when the package is being formed, and marginal portions overlapping and adhesively secured to the marginal portions of the outer elements of the package. 75

2. A package of flat structural elements of similar size and shape, comprising a plurality of such elements arranged in stacked relation, and means for securing said elements together in such relation, said means comprising thin relatively tough binding strips of thin paper or fibrous material having similar flexibility each having an intermediate portion covering an edge of the stack of said elements and marginal portions overlapping and adhesively secured to the marginal portions of the outer elements of the package, said strips being applied to opposite edges of the stack while the latter is under compression, whereby intermediate elements of the package are firmly secured in position by friction between one another and between said intermediate elements and the inner surfaces of said outer elements. 90

3. A package of flat structural elements of similar size and shape, comprising a plurality of such elements arranged in stacked relation, and means for securing said elements together in such relation, said means comprising two thin relatively tough binding strips of thin paper or fibrous material having similar flexibility respectively having intermediate portions covering opposite edges of the stack of said elements, and non-overlapping marginal portions extending over the marginal portions of the outer elements of the package and adhesively secured to the outwardly presented surfaces of such outer elements, said binding members being applied to opposite edges of the stack while the latter is under some substantial compression, whereby intermediate elements of the package are firmly secured in position by friction between one another and between said intermediate elements and the inner surfaces of said outer elements. 105 110

4. A package of substantially planar elements of similar size and shape each having two substantially parallel opposite boundaries comprising a plurality of such elements arranged in stacked relation with their said corresponding opposite boundaries in substantial alignment, and means for securing 125 130

5 said elements together in such relation, said means comprising two thin relatively tough binding strips of thin paper or fibrous material having similar flexibility respectively enclosing said two opposite boundaries of said stacked elements, each of said fibrous members having an intermediate portion under tension due to the application of substantial compacting force to said elements when said fibrous members are applied.

10 5. A package of substantially flat rectangular sheets of gypsum board of the nature and having the uses set forth in the specification, comprising a plurality of such sheets arranged in stacked relation with corresponding edges substantially in alignment and means for retaining said sheets in such relation, said means comprising thin relatively tough binding strips of thin paper or fibrous material having similar flexibility extending along and substantially completely enclosing two opposite edges of the stack and adhesively secured to the top and bottom sheets of the stack whereby said top and bottom sheets are retained in position for handling or stacking.

15 6. A package of substantially flat rectangular sheets of gypsum board of the nature and having the uses set forth in the specification, comprising a plurality of such sheets arranged in stacked relation with corresponding edges substantially in alignment and means for retaining said sheets in such relation, said means comprising thin relatively tough binding strips of thin paper or fibrous material having similar flexibility extending along and substantially completely enclosing two opposite edges of the stack and adhesively secured to the top and bottom sheets of the stack whereby said top and bottom sheets are retained in position for handling or stacking.

20 7. A package of substantially flat rectangular sheets of gypsum board of the nature and having the uses set forth in the specification, comprising a plurality of such sheets arranged in stacked relation with corresponding edges substantially in alignment and means for retaining said sheets in such relation, said means comprising thin relatively tough binding strips of thin paper or fibrous material having similar flexibility extending along and substantially completely enclosing two opposite edges of the stack and adhesively secured to the top and bottom sheets of the stack whereby said top and bottom sheets and the binding strips serve as the only means for retaining the remaining sheets of the package.

25 8. A package of substantially flat rectangular sheets of gypsum board of the nature and having the uses set forth in the specification, comprising a plurality of such sheets arranged in stacked relation with corresponding edges substantially in alignment and means for retaining said sheets in such relation, said means comprising thin binding strips of thin, relatively tough material having the essential characteristics of cheapness and flexibility extending along and substantially completely enclosing two opposite edges of the stack and adhesively secured to the top and bottom sheets of the stack whereby said top and bottom sheets are retained in position for handling and shipment.

30 9. A package of substantially flat rectangular sheets of gypsum board of the nature and having the uses set forth in the specification, comprising a plurality of such sheets arranged in stacked relation with corresponding edges substantially in alignment and means for retaining said sheets in such relation, said means comprising thin binding strips of thin, relatively tough material having the essential characteristics of cheapness and flexibility extending along and substantially completely enclosing two opposite edges of the stack and adhesively secured to the top and bottom sheets of the stack whereby said top and bottom sheets are retained in position for handling or stacking.

35 10. A package of substantially flat rectangular sheets of gypsum board of the nature and having the uses set forth in the specification, comprising a plurality of such sheets arranged in stacked relation with corresponding edges substantially in alignment and means for retaining said sheets in such relation, said means comprising thin binding strips of thin, relatively tough material having the essential characteristics of cheapness and flexibility extending along and substantially completely enclosing two opposite edges of the stack and adhesively secured to the top and bottom sheets of the stack whereby said top and bottom sheets and the binding strips serve as the only means for retaining the remaining sheets of the package.

40 In witness whereof, I have hereunto subscribed my name.

CHARLES R. BIRDSEY.
